UNITED STATES PATENT OFFICE.

THOMAS S. PUKERUD, OF WILKINSBURG, PENNSYLVANIA, ASSIGNOR TO WESTINGHOUSE ELECTRIC AND MANUFACTURING COMPANY, A CORPORATION OF PENNSYLVANIA.

OPERATING MECHANISM FOR CONTROLLERS.

1,299,779.

Specification of Letters Patent.

Patented Apr. 8, 1919.

Application filed March 28, 1917. Serial No. 153,088.

To all whom it may concern:

Be it known that I, THOMAS S. PUKERUD, a citizen of the United States, and a resident of Wilkinsburg, in the county of Allegheny and State of Pennsylvania, have invented a new and useful Improvement in Operating Mechanisms for Controllers, of which the following is a specification.

My invention relates to operating mechanisms for controllers such as are employed in connection with electric motors, and it has for its object to provide a device of the character indicated which may be operated either manually or by a power device, at the will of the operator.

In the operation of the controllers that are normally actuated by pilot motors or other power devices, it is sometimes necessary or desirable to adjust the controllers by manually operable means. This is especially true with reference to controllers that are employed in connection with the driving motors of printing presses, machine tools and many other machines.

I provide an arrangement consisting of a controller shaft that is adapted to be operated normally by a pilot motor which is operatively connected to the shaft by means of gear mechanism. A lever, which is pivotally connected to the controller shaft, is provided with means for detachably engaging one of the gear wheels. The lever is provided with a handle by means of which it may be actuated into and out of engagement with the coacting gear wheel. The controller shaft may thus be actuated manually independently of the pilot motor or it may be driven by the latter when the handle is released. The arrangement covered by the present application is similar to, and is an improvement upon, that shown and described in my copending application, Serial No. 98,796.

In the accompanying drawing, Figure 1 is a plan view of a controller with my invention applied thereto, parts being broken away. Fig. 2 is an end view of a portion of the operating mechanism shown in Fig. 1. Fig. 3 is a side view, partially in elevation and partially in section, of the mechanism shown in Fig. 1.

A base plate 1 of suitable insulating material supports a series of stationary contact members 2. A movable contact member 3,

which coacts with the stationary contact members 2, is carried by an arm 4. The arm 4 is rigidly secured to, and insulated from, a rotatable shaft 5.

A pilot motor 7, which may be, for example, an electric motor, is operatively connected to the shaft 5 by means of a worm 8, a worm wheel 9, a pinion 10 that is secured to the worm wheel, and a gear wheel 11 that is rotatably mounted upon the shaft 5.

A lever 12, which is pivotally connected to the shaft 5, is provided, at one end, with tooth-like projections 14 for engaging the teeth of the gear wheel 11. The lever 12 is provided, at its other end, with a manually operable handle 15. A spring 16 normally maintains the lever 12 in engagement with the gear wheel 11.

An electromagnetic brake 17 engages a wheel 18 on the shaft of the pilot motor 7 when the mechanism is at rest. A casing 19 partially incloses the gear mechanism for connecting the motor to the controller shaft.

In the normal operation of the mechanism, the controller arm 4 is adjusted to any desired position by completing the circuit of the pilot motor 7 for operation in the desired direction. In case, however, it is either necessary or desirable to adjust the controller manually or to change the relation of the controller arm to the pilot motor 7, the handle 15 is actuated downwardly to effect the disengagement of the lever 12 from the gear wheel 11. The shaft 5 may then be adjusted to any desired position by the manual actuation of the handle 15 and the lever 12.

Upon the release of the handle 15, the spring 16 actuates the lever 12 into engagement with the gear wheel 11. In case the projections 14 do not mesh with the teeth of the gear wheel 11, this action occurs substantially immediately upon the rotation of the gear wheel 11 by the pilot motor.

While the arrangement described above is particularly adapted for use in connection with printing presses and similar machines, it is capable, also, of being employed in connection with any other mechanism in which similar operating characteristics are desirable.

I claim as my invention:

1. The combination with a rotatable element and a gear wheel rotatably mounted

- thereon, of a manually operable lever pivotally connected to said element and detachably engaging said gear wheel, and a power device operatively connected to said gear wheel.
2. In a controller, the combination with a shaft, a motor and means for operatively connecting said motor to said shaft, said means comprising a gear wheel mounted on said shaft and a lever, of a handle connected to said lever for effecting the disconnection of said motor and said shaft and for actuating said shaft manually.
3. The combination with a rotatable element and a power device, of gear mechanism for operatively connecting said device to said element, one member of said gear mechanism being rotatably mounted on said element, and a manually operable member movably connected to said element for detachably engaging said gear member.
4. The combination with a movable arm and an actuating motor therefor, of means for operatively connecting said motor to said arm, said means comprising a gear wheel rotatable relatively to said arm, and a manually operable lever pivotally connected to said arm and engaging said gear wheel.
5. The combination with a movable member, a gear wheel rotatably mounted thereon and a motor operatively connected to said gear wheel, of a lever pivotally connected to said member and detachably engaging said gear wheel, and a spring for yieldingly maintaining the operative connection of said lever and said gear wheel.
6. The combination with a movable member, a gear wheel rotatably mounted thereon and a motor operatively connected to said gear wheel, of a lever pivotally connected to said member and detachably engaging said gear wheel, a handle on said lever for actuating it out of engagement with
- said gear wheel, and a spring for yieldingly maintaining the engagement of said lever and said gear wheel.
7. The combination with a movable member, a gear wheel rotatably mounted thereon and a motor operatively connected to said gear wheel, of a lever pivotally connected to said member and having means for engaging the teeth of said gear wheel, a handle for controlling the position of said lever and for actuating said movable member independently of said motor, and a spring for yieldingly maintaining the engagement of said lever and said gear wheel.
8. The combination with a member rotatable about an axis and a gear wheel rotatable relatively thereto about said axis, of power mechanism for rotating said gear wheel and means for causing said member to rotate with said gear wheel or independently thereof.
9. The combination with a member rotatable about an axis, power mechanism and means comprising a second member mounted on said axis for operatively connecting said first member to said mechanism, of means for connecting said members to cause them to be rotated together by said mechanism and means for rotating said first member independently of said second member.
10. The combination with a plurality of stationary contact members, of a movable contact member for coöperating therewith and rotatable about an axis, an element rotatable about said axis relatively to said movable contact member, means engaging said element to cause said rotatable member to rotate with said element or independently thereof and power means for rotating said element.

In testimony whereof, I have hereunto subscribed my name this 22nd day of March, 1917.

THOMAS S. PUKERUD.
